UNITED STATES PATENT OFFICE.

CHARLES A. ADAMS, OF DORCHESTER, MASSACHUSETTS.

CANDY-BOX.

SPECIFICATION forming part of Letters Patent No. 722,199, dated March 10, 1903.

Application filed February 2, 1903. Serial No. 141,429. (No model.)

To all whom it may concern:

Be it known that I, CHARLES A. ADAMS, a citizen of the United States, residing at Dorchester, in the county of Suffolk and Commonwealth of Massachusetts, have invented certain new and useful Improvements in Candy-Boxes, of which the following is a full, clear, and exact description, reference being had to the accompanying drawings, forming a part 10 of this specification.

This invention has for its object to provide a new and improved box in the shape of a toy bird-house, preferably a chicken-house, with an imitation rope fence around a chicken-garden, the chicken-house being designed and so arranged as to conceal from view another box which is adapted to hold for its contents candy, nuts, or similar articles, the outer or house box being arranged in the form of an 15 Easter novelty for use as an ornamentation or as a toy for children after its use as a candy-box has been fulfilled. Its novel construction, arrangement, and combination of parts 20 will be substantially as hereinafter described and claimed.

In the accompanying drawings, Figure 1 shows a perspective view of my box as it will look when closed. Fig. 2 is a side sectional view of the candy-box, the chicken-house, and 25 its contiguous parts.

In the drawings, *a* represents the chicken-house, and *b* the ground or flooring upon which it rests. The house *a* consists of the two end pieces *g g* and the two side pieces *h h*, 30 connected by a horizontal piece *m*, which part serves as a cover to the inner box. The end pieces *g g* extend upward to a point and carry the slanting pieces *i i*, which serve as a roof to the chicken-house. Upon the sides of the 35 box may be painted windows, chicken-doors, &c., the whole being arranged so as to entirely cover the inner box proper, which inner box is adapted to hold candy and consists of the bottom part *j* and the four side walls *k*. The 40 bottom *j* is fastened to a second bottom piece *b*, which is arranged to extend beyond the sides *k* of the inner box and also beyond the

50 sides *h* of the outer box and serve as an ornamental base for the house, and the piece *b* may be extended considerably beyond one of the sides *h*, as at *b'*, so as to allow of an imitation chicken-yard, which may consist of the gold or silver cord or other string made to represent a rope fence attached to one or more fence-posts *e, e', e², and e³*. Within the 55 chicken-yard or upon the box part *a* may be fastened one or more birds or chickens.

Having thus described my invention, what I claim, and desire to secure by Letters Patent, is—

60 1. A candy-box, in the shape of a bird-house, having inner and outer boxes, the inner box adapted to hold candy, the outer box provided with a slanting top and having an imitation covering to represent a bird-house, 65 and one or more imitation birds attached to the top of the box, a partition extending across the inner upper part of said box and adapted to form the cover to the inner box, the outer box arranged to conceal the inner box, and 70 the inner box affixed to a secondary base extending beyond the sides of the outer box, substantially as shown and described.

2. A candy-box, in the shape of a chicken house and yard, having inner and outer boxes, 75 a secondary bottom fixed to the inner box which extends beyond the walls of said outer box and having on one side thereof an imitation fence, the outer box having an imitation covering to represent a chicken-house, the inner box adapted to hold candy, nuts, or the like and to be entirely concealed by the outer box, and one or more chickens attached to the top of the box or upon the secondary platform 80 of the inner box, substantially as shown and 85 described.

In testimony whereof I have hereunto set my hand in the presence of two subscribing witnesses.

CHARLES A. ADAMS.
